UNITED STATES PATENT OFFICE.

ALFRED BUTCHER, OF ROSELLE PARK, NEW JERSEY.

MEANS FOR BURNING POWDERED FUEL.

Application filed July 14, 1926. Serial No. 122,360.

My invention relates to burners and has particular relation to means for and method of burning powdered fuel.

One object of my invention is to provide an apparatus of the character described which shall be of simple, compact and rugged design and shall lend itself to inexpensive quantity production methods of manufacture, the several parts of which may be made on existing automatic machinery and assembled with a minimum expenditure of time and money.

Another object of my invention is to provide a method of burning powdered fuel which consists in causing the fuel to approximate the form of an expanding cone, wherein the fuel is moved spirally, and subjecting said cone to a contracting cone of air, wherein an opposite spiral movement occurs.

A further object of my invention is to provide a method which consists in forming a spirally moving mass of powdered fuel in the shape of an expanding cone, intermingling therewith a second expanding cone formed by an auxiliary fuel and subjecting both fuels to air currents in the form of a contracting cone.

A still further object of my invention is to provide a burner for powdered fuel that shall be particularly applicable to small furnaces by reason of its relatively short flame.

A still further object of my invention is to provide a burner of such design that the radiant heat from the furnace may be prevented from directly striking the furnace front plate structure as well as substantially the entire exposed surface of the fuel discharge passage.

A still further object of my invention is to provide a burner of the character described having means whereby the combustion conditions within the flame may be ascertained from a remote point.

A still further object of my invention is to provide means whereby the heavier portions of the powdered fuel may be discharged from the burner into a desired portion of the flame.

Other objects and applications of my invention, as well as details of construction and operation, whereby my invention may be practiced, will be apparent more fully hereinafter, when taken in connection with the accompanying drawings, wherein

Figure 1 is a vertical longitudinal section

of a burner embodying the preferred form of my invention, showing the same mounted in a furnace wall;

Fig. 2 is a rear elevation of the structure shown in Fig. 1;

Fig. 3 is a rear view of the stationary portion of the air register shown in Fig. 1;

Fig. 4 is a view of the air register shutter;

Fig. 5 is an elevation of one of the deflectors mounted in the fuel discharge passage of burner;

Fig. 6 is a transverse section taken approximately on the line 6—6 of Fig. 5;

Fig. 7 is a detail section as seen from the line 7—7 of Fig. 1.

Fig. 8 is a detail vertical longitudinal section of certain of the parts illustrated in Fig. 1, showing a slightly modified form of burner and its associated feed pipe;

Fig. 9 is a view similar to Fig. 1 showing another embodiment of my invention; and

Fig. 10 is a rear elevation of the structure shown in Fig. 9.

Referring to the preferred embodiment of my invention shown in Figs. 1 to 7, inclusive, the furnace wall 1 is provided with a passage 2 extending therethrough from the front side 3 to the rear side 4.

The passage 2 is composed of two portions designated 5 and 7.

The portion 5 is preferably formed to receive a shell comprising a spherical portion 6 and a tubular portion 9, the inner end of the portion 6 terminating at a distance 20 from the rear side 4 of the wall.

The portion 7 comprises the rear part of the opening 2 not occupied by the shell 6, and, as shown, the portion 7 is flared outwardly from the inner edge of the shell to the rear side 4 of the furnace wall, so as to provide a conical outlet having an increasing diameter.

A transversely extending annular flange 12 is formed on the front of the shell. This flange is bolted to a plate 13 that is positioned in front of the furnace wall, being spaced slightly therefrom.

The plate 13 has an opening 11 therein which is of slightly less diameter than the diameter of the flange 12, but the opening 11 is of sufficient diameter to permit the shell 6 to be inserted therethrough when the parts are being assembled.

The burner apparatus is disposed within the shell 6. Powdered fuel may be conveyed to such apparatus through an exter-

nally positioned casing in the form of a pipe 14. This pipe is so designed that currents of air may be used to force the fuel into the burner.

5. Mounted within the end of the shell is an air register 18. This register comprises a central tubular portion 30 and outer and inner flanged ends 17 and 25, respectively.

The outer end of the portion 30 of the air register aligns with the inner end of the pipe 14. In order to permit the outer end of the register to be secured to the inner end of the pipe 14, the inner end of the latter is formed with a flange 16 which is bolted to the flange 17 of the air register.

The register 18 is carried by the plate 13. For this purpose, the periphery of the flange 17 is secured to the flange 12 of the shell 6 by means of bolts 19.

20. The flange 17 of the register 18 closes the end of the shell 6. However, to permit air currents to pass inwardly through the shell, openings 21 are formed in the flange 17.

Webs 22 are formed on the exterior of the tubular portion 30 of the air register between the flanges 17 and 25 thereof. These webs are so disposed with respect to the central tubular portion of the register and the opening 21 in the flange 17 as to provide a plurality of air deflecting vanes that are adapted to impart a spiral movement to the air currents flowing through the openings 21 into the shell 6.

25. The volume of air passing through the openings 21 of the air register may be controlled by a shutter 26. Preferably the shutter is in the form of a perforated circular plate mounted for rotation in a recess 27 formed in the front face of the flange 17 of the air register 18, and retained therein by a ring 28.

The center of the shutter is formed with a relatively large circular opening 32 in which is inserted the inner end of the pipe 14. If 30. so desired, the flange 16 of the pipe 14 may be cut as shown in Fig. 1, so as to engage the portion of the shutter surrounding the opening 32, and, thereby retain the central portion of the shutter in position.

35. The shutter 26 is provided with openings 29 that are similar in form to the openings 21 of the air register.

The openings 29 are adapted in one position to register directly with the openings 21. A movement, however, of the shutter causes a partial closing of the openings 21, depending upon the extent of movement, so that the air supply for the burner at this point may be decreased, or completely cut off, and reliance had merely upon the air employed to carry the powdered fuel to the burner.

Attached to the flange 25 of the air register 18 is a flange 24 of a burner nozzle 31. This nozzle comprises a tube that is longitudinally disposed in alignment with the portion 30 of the register.

The inner end or tip of the nozzle 31 is contracted to provide a restricted outlet 35.

The burner outlet is so designed that the fuel discharged therefrom may be caused to assume the form of an expanding cone.

As a result of so converging the walls of the discharge passage at the burner outlet 35, the cone is of such character that the velocity of the fuel will be substantially zero at a relatively short distance from the burner.

For example, combustion may be completed within a zone seven feet from the burner, as compared with a zone of twenty-five feet from the usual type of burner.

In order that the heavier portions of the fuel normally settling to the bottom of the nozzle 31 may be discharged into the top of the flame, as well as into the side and bottom of the flame, I provide a deflector 36 (see Figs. 1, 5 and 6).

The deflector 36 comprises a pair of spaced circular walls which are interconnected by a plurality of radially disposed webs 37.

Intermediate successive webs 37 are vanes 39.

The vanes 39 are of such dimensions and are so disposed between the spaced circular walls of the deflector as to leave apertures 38 for the passage of the powdered fuel.

The vanes 39 are also inclined with respect to the webs 37 so that a spiral movement will be imparted to the fuel. The inclination of the vanes is such that the spiral movement imparted to the fuel will be in a direction opposite to the spiral movement of the air currents flowing through the air register.

The position of the deflector 36 relative to the outlet 35 of the nozzle 31 also controls the effect of the deflector on the flame.

Therefore, in order to provide means for adjusting the relative position of the deflector 36 with respect to the outlet 35, I provide a tubular adjusting rod 41.

The rod 41 is disposed longitudinally in the air register 18 and the nozzle 31, and projects outwardly through an opening 44 in the pipe 14.

The inner end of the rod 41 may terminate adjacent to the outlet 35, as shown by Fig. 1.

The inner end of the rod 41 has a threaded portion 42 which is engaged by a threaded aperture 43 formed centrally in the deflector 36.

The portion of the pipe 14 in which the opening 44 is formed has a flange 46.

The end of the rod 41 has a threaded portion 51 on to which is screwed a plate 48.

The plate 48 engages with the flange 46, and is secured thereto by means of bolts 47.

As the member 41 is tubular throughout its length, it provides a sight hole that permits accurate observation of the combustion conditions within the flame from an external point.

Should the fuel be very coarse, it is desirable to provide the burner with a second deflector.

Such deflector, indicated by the numeral 52, may be mounted in the fuel passage in advance of the deflector 36, as shown by Fig. 1. If so disposed, the deflector 52 will be positioned within the air register 18.

The deflector 52 may be similar in form to the deflector 36 previously described, but the vanes thereof should be inclined in a direction opposite to the vanes of the deflector 36, so that the fuel will be given a spiral movement in the same direction as the direction given to the air which is deflected by the vanes of the air register 18, but in the opposite direction to that caused by the vanes 39 of the deflector 36.

The deflector 52 is provided with a central threaded aperture 53 for engagement with a threaded portion 54 on the member 41.

The threaded portions 53 and 54 have a pitch opposite to those for the deflector 36, so that the two deflectors may be moved towards each other or away from each other upon the turning of the member 41.

The deflectors 36 and 52 have lugs 45 formed on their peripheries (see Fig. 5), which lugs are mounted in a groove 33 formed longitudinally in the bottom of the fuel passage (see Fig. 1).

In this manner the deflectors will be prevented from turning in the bore of the fuel passage when the member 41 is actuated.

A radiation cone or deflector 55 is mounted on the discharge end of the nozzle 31.

The deflector 55 comprises a pair of spaced inner and outer walls 56 and 57, respectively.

As shown clearly in Fig. 1, the walls of the deflector are spherically curved in the direction of the discharge outlet 35 of the burner.

Interconnecting the walls 56 and 57 of the deflector 55 are webs 58. These webs provide a plurality of air passages 59.

Due to the contour of the walls of the deflector 55 the air passages 59 have enlarged open ends 61 facing the furnace front and restricted outlets in proximity to the discharge outlet of the burner.

The inner wall 56 of the deflector 55 may be supported in spaced relation to the nozzle 31 by means of extensions 63 formed inwardly from the walls 58.

This construction enables the deflector 55 as a unit to be moved longitudinally on the burner for a limited distance.

The inner edges of the walls 56 and 57 of

the deflector 55 are interconnected by a wall 66 of the frusto-conical form.

The wall 66 is disposed inwardly from the outer spherical wall 57.

Formed in the wall 66 are a plurality of air outlet openings 67.

The tip of the burner 31 is kept cool by the flow of air through the space between its exterior and the inner wall 56 of the deflector 55.

The walls 56 and 57 of the deflector 55 are likewise cooled by the air currents flowing therebetween.

The space between the outer wall 57 of the deflector 55 and the shell 6 forms an air passage 69.

The passage 69, due to the contour of the deflector 55 and the shell 6 converges towards the burner outlets.

The air currents (indicated by arrows in Fig. 1) traversing the passage 69 form a contracting cone wherein a spiral movement occurs, which movement is opposite to that imparted to the fuel by the deflector 36.

When the powdered fuel in the form of an expanding cone is discharged through the outlet 35 of the burner, it mixes with the contracting cone of air flowing through the openings 67 in the deflector 55, and a substantially straight line motion will be imparted to the flame.

By reason of the fact that the fuel and air have opposite spiral movement, a thorough mixing of the air and fuel is insured. This consequently results in greater burner efficiency.

The angle of the flame may be varied by moving the deflector 55 towards or away from the furnace front the limiting position being when the fuel cone just clears the outlet opening 8 as well as the outwardly flaring portion 7. A further function of the deflector 55 is the prevention of the disintegration of the furnace front by the radiant heat from the furnace.

To this end the walls 57 and 66 of the deflector 55 are so designed that radiant heat passing through the shell is prevented from directly striking parts comprising the furnace front plate structure, viz., the flange 17 and the air control shutter 26 of the air register 18, and the wall of the tubular opening 9 in the shell 6.

The walls 57 and 66 also prevent radiant heat from directly striking the remaining portions of the air register, as well as all but a relatively small edge portion of the burner outlet 35.

The inner wall 56 also serves to prevent such radiant heat as passes through the air outlet 67 in the deflector 55 from striking directly the burner parts just noted.

In operation, powdered fuel is conveyed through the tubular portion 30 of the air register and the burner nozzle 31 by means

of air currents. As the fuel passes through the deflector 36 it is given a spiral movement which it maintains upon being discharged through the outlet 35 of the nozzle

5 31. The converging walls of the burner outlet cause the swirling fuel to spread out in the form of an expanding cone. The dimension of this cone is partially determined by the position of the deflector 55 relative to 10 the discharge end of the nozzle.

The cone of fuel is subject to air currents which enter the shell 6 through the openings 21 in the air register 18 and are discharged through the air passages 67 in the form of a 15 contracting cone having a spiral movement reverse to that imparted to the fuel by the deflector 36.

Due to the construction of the wall 56 of the deflector 55, and due also to the relative position of the deflector to the outlet of the burner a space 64 is provided around the tip of the burner through which space air is supplied to the fuel immediately adjacent to the tip of the burner.

25 35. The current of air flowing through the space 64 will maintain the tip of the burner in a relatively cool condition.

When such powdered fuels as anthracite coal, coke, oil refinery coke, breeze and other 30 fuels low in volatile hydrocarbons are to be used, I provide the apparatus with an auxiliary fuel burner 71. This form of the invention is shown by Fig. 8.

The burner 71 may be positioned within 35 the fuel discharge passage 35 of the nozzle 31, and be supplied with fuel through a feed pipe 72 passing through the tubular member 41 and supported thereby.

The burner 71 is so designed that the fuel 40 passes therefrom in the form of an expanding cone which mixes with the powdered fuel passing from the discharge outlet 35 of the nozzle 31, thereby providing an extremely valuable fuel.

45 50. When this form of the invention is used the cones of fuel are subjected to the air currents that enter the shell 6 through the openings 21 of the air register 18 and through the air passage 69 in the form of a contracting cone having a spiral movement opposite to that imparted to the pulverizing fuel by the deflector 36 in a manner similar to that previously described.

As shown in Figs. 9 and 10, my invention 55 also embodies an alternative form of cone deflector in which a single spherical wall 74 is used. This deflector has one end 75 disposed contiguous to the discharge end 35 of the nozzle 31. The end 75 is provided 60 with a relatively short outwardly flaring flange 76. The flange is so designed as to insure a maximum spreading of the burner flame.

The end 75 of the deflector is spaced

slightly from the discharge end 35 of the nozzle 31 so that the latter will be cooled by air currents flowing through the deflector.

The wall 74 of the deflector and the shell 6 70 form a passage 77 that functions in a manner similar to the passage 69 shown in Fig. 1.

The supply of air to the passage 77 may be increased by forming longitudinal slots 78 in the wall 74 of the deflector near the outer edge thereof. These slots are cut through the wall 74 on an angle so that the air flowing therethrough will be caused to swirl in the same direction as is produced by the vanes of the air register 18.

The passage of the air through the slots 78 also results in a further cooling of the wall 74.

The contour of the wall 74 is such that the deflector shown in Figs. 9 and 10 has its outer surface formed with a curvature, the radius of which is shorter than the radius of curvature of the outer wall of the deflector 55. Hence, radiant heat will be prevented from striking the important parts of the burner nozzle, and the slots 78 are so inclined that the radiant heat cannot pass directly through the same.

The operation of the structure shown in Figs. 9 and 10 is otherwise the same as indicated for the preceding figures of the drawings, however, it should be noted that the cone deflector last described differentiates over the preferred embodiment of the invention in the elimination of the inner wall 56 and the apertured inner end wall 66.

While I have shown only certain embodiments of my invention, for the purpose of describing the same and illustrating its principles of construction and operation, it is apparent that various changes and modifications may be made therein without departing from the spirit of my invention, and I desire, therefore, that only such limitations shall be imposed thereon as are indicated by the appended claims or as are demanded by the prior art.

What I claim is:

1. The combination with a furnace wall having a spherically formed opening therein, of a shell mounted within said opening, said shell having an open end provided with a laterally projecting flange, a plate disposed in front of said wall, means for securing said flange to said plate, a burner tube disposed within said shell, an air register disposed coaxially with said tube, said air register having a flange overlapping the flange of said shell and secured thereto, said flange having openings formed therein, a plurality of vanes extending from the edge of said openings inwardly of the said air register, and a rotary shutter mounted in

the front of air register flange, and having openings aligning with the openings in said air register flange.

2. The combination with a furnace wall having a spherically formed opening, of a shell mounted within said opening, a burner tube disposed within said shell, means for deflecting fuel through the burner tube and for imparting a spiral movement thereto, means surrounding the burner tube and clos-

ing one end of the shell for delivering spiral air currents through the shell, and a deflector mounted on the discharge end of the burner tube, said deflector having inner and outer spherically curved walls, a plurality of interconnecting spacing walls forming passages, and an apertured end wall of frusto-conical form interconnecting the said curved walls. 15

ALFRED BUTCHER.
